dian

Application July 13, 1939, Serial No. 284,318
In Germany April 6, 1938

7 Claims. (Cl. 122—451)

The present invention relates to vapor generators or boilers and more especially to those of the "once-through" type, and is particularly concerned with regulating apparatus for such generators or boilers.

It has been proposed in connection with once-through boilers to regulate the supply of feed water automatically and in accordance with the steam consumption. It has been found, however, that for still partially unexplained reasons, the effect of an increase or decrease of the feed water supply to the boiler is felt in the steam generating zone only after a relatively long time lag of the order of about ten minutes. Thus, there is an insufficient rate of feed water to the boiler during this period, while an increased quantity of steam is withdrawn. This results in a shifting of the evaporation zone and thereby changes the effective length of the superheater section of the boiler. Furthermore, the phenomena referred to make it almost impossible to keep the temperature of the steam constant, especially in case of rapid load changes.

It has also been proposed to provide in connection with once-through boilers, in addition to the main feed line connected to the boiler inlet, an auxiliary feed line by means of which a part of the feed water is introduced directly into the vaporizing or into the superheating section of the boiler. In this prior proposal a loaded valve was to be mounted in the auxiliary feed line and was adapted to be kept closed by the pressure in the boiler. Thus, with this arrangement, a supply of auxiliary water to the boiler only occurs when the pressure in the latter has fallen by a considerable degree. Furthermore, the valve only shuts off the auxiliary supply of feed water again when the pressure in the boiler resumes its original value. Since, however, there is a lapse of time, viz. the vaporization period, between the admission of the auxiliary water supply and the rise in pressure caused thereby, the valve in the auxiliary feed line will not close early enough, and it will thus be impossible to avoid very considerable fluctuations in the pressure. In addition, the valve is in no way responsive to pressure increases in the boiler due to a reduction in the load.

It is an object of this invention to arrange the regulation of the feed, where use is made of an auxiliary boiler feed, such that both in the case of positive and in the case of negative variations in the load, the pressure in the boiler remains constant and without fluctuations.

Thus, the present invention provides regulating apparatus for once-through boilers or vapor generators wherein an auxiliary feed water conduit is connected to the vaporizer or superheater section of the boiler or generator, and is used in addition to a main feed water conduit connected to the inlet. The amount of auxiliary feed water is proportioned to the variation in load, and to the rate of variation in load by means of a valve (in the auxiliary feed line) which is controlled by a regulator that receives corresponding impulses from pressure means connected to the boiler, and a suitable counter-balancing impulse from pressure means in the auxiliary feed water line.

It is also known to spray cooling water into the steam line or the superheater of a boiler for the purpose of regulating the steam temperature. In the known arrangements utilizing this principle the cooling water was regulated in response to the temperature, whereas the feed water was regulated in accordance with the load. In accordance with a further feature of the present invention, however, the supply of feed water at the inlet of the boiler is set to a predetermined basic load, and the injected water is regulated in accordance with fluctuations in the load.

This method of regulation can, however, only be successful in cases where the fluctuations in the load are small as compared with the basic load.

If, therefore, fluctuations which are large in relation to the basic load are to be anticipated, the supply of feed water at the inlet of the boiler must be regulated in response to the load in the conventional manner. In such instances, to compensate the delay caused by the phenomena referred to above, the injected water may, in accordance with another feature of this invention, be controlled in the auxiliary feed line by the rate of variation of the load. Thus, if there is a sudden increase in the load at the inlet of the boiler, a correspondingly increased volume of feed water will be allowed to pass at the inlet, although this will only become effective in the boiler after a lapse of time. During the change in load, however, there will be simultaneously passed through the auxiliary feed line, and directly to the vaporization zone of the boiler, a quantity of water which is greater according as the variation in the load is more sudden.

It is also of advantage to control the supply of fuel to the boiler furnace as a function of the rate of variation of the load, so that the

heat of the furnace is increased more rapidly according as the rate of variation of the load becomes greater.

In a preferred form of the invention the regulator includes a power relay, and in order to transmit the rate of change in the load to this relay, two oppositely acting pressure responsive devices or systems may be actuated by impulses, one of which is represented as a measuring pressure, and the other of which is also controlled by a constriction, e. g., a nozzle or capillary tube. If the effective surfaces of the pressure devices are chosen of the same size, the relay will receive an impulse which is independent of the absolute value of the load and only dependent upon the rate at which the load varies, and which will thus only be effective during a variation in the load. If, on the other hand, the surface of the pressure device which receives the impulse directly is larger than the surface of the other device, as long as the same pressure obtains in the two devices, the difference in the forces exerted by the two devices will be exerted on the relay. This difference in the force is, however, a function of the absolute value of the pressure, i. e., of the load. Thus, if in a system of this kind the load is increased, the force exerted by the larger pressure device will temporarily become smaller, that is until a balance in pressure is set up between the two devices through the constriction. The impulse which acts on the relay is therefore dependent both on the absolute value of the load and the rate of variation thereof. In this way it is possible to distribute the regulation of the feed water in accordance with the load to both regulations, viz. to the main feed water conduit and the auxiliary feed water conduit.

Embodiments of the invention are illustrated by way of example in the accompanying drawings, in which

Fig. 1 is a diagrammatic illustration of a boiler plant conforming to this invention;

Fig. 2 is a diagram of the variation of the feed water supply in the plant of Fig. 1;

Fig. 3 is a diagrammatic illustration of a second embodiment of a boiler plant according to the invention;

Figs. 4a-4d are diagrams which will be used hereafter to explain the operation of the plant of Fig. 3;

Fig. 5 illustrates another embodiment of the invention; and

Fig. 6 shows diagrams related to the operation of the plant illustrated in Fig. 3.

In Fig. 1 the reference 1 designates the tubular system of a once-through boiler which is supplied with water through a feed water line 2. At the inlet to the boiler is a feed water valve 3 which is controlled by a servo-motor 4 operated by an equalizing regulator 5. The quantity of feed water passing through the valve 3 is measured by the difference in pressure between two sides of a constriction 6 in the line 2, and is kept constant by the regulator 5 at a value corresponding to a fundamental value determined by an adjustable spring 7 which also acts on the regulator 5. The regulator is preferably of the well known "Askania" type.

In the diagram shown in Fig. 2, the quantity of feed water passing through valve 3 is represented by the curve a.

An auxiliary feed water conduit 8 is branched off the feed water conduit 2 and communicates with the vaporizing and/or superheater section

9 of the boiler tube 1. Arranged in the conduit 8 is a regulable valve 10 and a measuring constriction 11.

The valve 10 is controlled by a regulator 12 through the intermediary of a servo-motor 13, in such manner that the quantity of water measured at 11 is dependent upon the pressure fluctuations in the steam delivery line 14. To this end, the pressure in the line 14 is transmitted through a measuring pressure conduit 15 to a bellows operated lever system 16 forming part of the regulator 12 and dependent on the variations in pressure in the line 14. The system 16 is provided with a counterweight 17 which is so designed that it allows for a quantity of water which is already regulated by the regulator 5 and corresponds to a basic load. In Fig. 2 the quantity of additional water which is controlled by the regulator 12 is indicated by the hatched area b, and the total quantity of feed water is represented by the curve c.

The spring 7 bears against and is supported by a safety device comprising a lever 18 controlled by a bellows 19 acted upon by the pressure in the conduit 15, and by a weight 20, the lever 18 being mounted for pivotal movement on a knife-edge 21. When a predetermined basic load is exceeded, the lever 18 is adapted to abut against a stop 22.

The plant described above operates as follows:

The lever 18 bears against the abutment 22 as long as the load on the boiler exceeds a predetermined basic load, and the valve 3 feeds to the boiler a quantity of water corresponding to the basic load which is set by the spring 7. If the load drops below this set basic value, the regulator 5 acts as a normal feed water regulator since the lever 18 will then be raised from the abutment 22 by the bellows 19 and the value to which the spring 7 is automatically set is varied in accordance with the load. This prevents the boiler from being overfed when the load is small.

Owing to the fact that the regulation of the feed water by the valve 3 is not perceptible in the vaporizer section until after a large time elapses, as explained above, additional water is injected into the vaporizer or superheater section 9, through the auxiliary line 8, and, in fact, the quantity of additional water is regulated in response to the load by the regulator 12. Thus, it is impossible for an insufficiency of water to occur in the vaporizing section due to the feed water lag.

In the embodiment illustrated in Fig. 3, a load-responsive regulator 5' of conventional construction is utilized for regulating the valve 3', and is so set that, for every load, the boiler is underfed by a predetermined amount.

The diagram in Fig. 4b shows the quantity of feed water controlled by the regulator 5', as the curve d and the desired quantity of water as the curve e running parallel to curve d.

In the embodiment of Fig. 3 the regulable valve 10' in the auxiliary conduit 8' is controlled by a regulator 12' which, when the load is constant permits the passage of the underfed quantity of water. This quantity of water is represented at the regulator 12' by the weight 17'.

The measuring pressure conduit 15' communicates in this embodiment, with a bellows 23. A second bellows 24 of the same dimensions as the one 23 and which is arranged to oppose its action, also communicates with the measuring pressure conduit 15' through a conduit 26 which

is constricted at 27. An air chamber 28 is connected to the conduit 26 at a point behind the constriction 27.

The measuring pressure conduit 15' and the bellows 23 and 24 are of course filled with condensate and the water also partly fills the air chamber 28. If the pressure in the conduit 15' increases, the level of the water in the air chamber will rise and the air which is still present will be compressed. This causes fluid to pass through the constriction 27 so as to set up a delayed balance in pressure between the bellows 23 and 24.

So long as there is no change in the load, the pressures on the bellows 23 and 24 remain balanced via the conduit 26, and the regulator therefore receives an impulse from the weight 17' only. As soon, however, as the load increases the pressure on the bellows 24 is temporarily greater and the regulator 12' receives an impulse which is greater according as the rate of change in the load is greater. Thus, during an increase or decrease of the load, the quantity of extra feed water is increased or decreased by the regulator 12' proportionately to the rate of variation of the load.

The curve *f* in Fig. 4c represents the additional quantity of water admitted by the regulator 12' when the load follows the course indicated by the curve *g*. In the Fig. 4d, the curve *h* represents the total quantity of feed water for which the regulators 5' and 12' are set. The supplementary amount of water which is brought into use when the load increases or decreases, but, due to the "filling-up" phenomena, only with a time lag, is here compensated by controlling the feed of additional water.

Fig. 5 illustrates a modification in which the bellows 23'' has a larger effective surface than the bellows 24''. The differential pressure which acts through the lever system on the regulator 12'' is dependent upon the load. The additional quantity of water passing through the auxiliary conduit 8'' and controlled by the regulator 12'' thus follows the curve *i* in the associated diagram of Fig. 6, and it will be seen that the quantity of this water is a function of the load and also of the rate of variation of the load. If two bellows of the same size were used the impulses transmitted by them would be a function of the differential pressure across the restriction 11'' and thus of the rate of pressure change in the line 14. This pressure, however, is a direct function of the rate of steam flow and therefore the differential pressure is a function of the rate of load change. When the size of the upper bellows 23'' is increased in size relative to the lower bellows an additional force is added which is directly proportional to the line pressure and thus of the load. The total force transmitted is therefore load rate change plus load change. The impulse representing the quantity of liquid is the one taken across restriction 11''.

It will be appreciated that an additional quantity of fuel can be supplied to the boiler furnace in response to variations in the load, and this extra supply can be controlled in an analogous manner to the control of the feed water as described above.

Having now particularly described and ascertained the nature of said invention and in what manner the same is to be performed, we declare that what we claim is:

1. Apparatus for automatically controlling the operation of a vapor generator having a once-through fluid passage receiving liquid at one end and delivering vapor at the other end, comprising a main feed conduit communicating with the inlet end of said passage, an auxiliary feed conduit leading to the vapor part of said passage, first impulse means responsive to the generator load variations, second impulse means responsive to the quantity of liquid flowing through the auxiliary conduit, and a control valve in said auxiliary conduit connected to be controlled by said first and said second impulse means.

2. Apparatus for automatically controlling the operation of a vapor generator having a once-through fluid passage receiving liquid at one end and delivering vapor at the other end, comprising a main feed conduit communicating with the inlet end of said passage, an auxiliary feed conduit leading to the vapor part of said passage, impulse means responsive to the quantity of liquid flowing through said main feed conduit, a relay acted upon by said impulse means, a servo-motor actuated by said relay, a control valve in said main feed conduit to be controlled by said servo-motor, means for exerting on said relay a counterforce in accordance with a predetermined generator basic load including means for decreasing said counter-force in response to the actual load in the region in which the actual load is smaller than said predetermined basic load, load impulse means responsive to the generator load variations, feed impulse means responsive to the quantity of liquid flowing through said auxiliary conduit, a control valve in said auxiliary conduit connected to be controlled by said load impulse means and said feed impulse means.

3. Apparatus as claimed in claim 1 in which said first impulse means are responsive also to the actual load.

4. Apparatus for automatically controlling the operation of a vapor generator having a once-through fluid passage receiving liquid at one end and delivering vapor at the other end, comprising a main feed conduit communicating with the inlet end of said passage, an auxiliary feed conduit leading to the vapor part of said passage, first impulse means responsive to the rate of generator load variations, second impulse means responsive to the quantity of liquid flowing through said auxiliary conduit, a control valve in said auxiliary conduit connected to be controlled by said first and said second impulse means, third impulse means responsive to the generator load variations, a control valve in said main feed conduit connected to be controlled by said third impulse means.

5. Apparatus in accordance with claim 1 in which said first impulse means comprise two pressure sensitive means acting in opposition to each other, one of said two pressure sensitive means communicating directly with a pressure which is responsive to the generator load, the other pressure sensitive means communicating with said pressure by means of a constriction.

6. Apparatus in accordance with claim 1 in which said first impulse means comprise two pressure sensitive means acting in opposition to each other, one of said two pressure sensitive means communicating directly with a pressure which is responsive to the generator load, the other pressure sensitive means having a smaller effective surface than the counter-acting pres-

sure sensitive means and communicating with said load pressure via a constriction.

7. Apparatus in accordance with claim 1 in which said first impulse means comprise two pressure sensitive means acting in opposition to each other, one of said two pressure sensitive means communicating directly with a pressure which is responsive to the generator load, the

other pressure sensitive means communicating with said pressure by means of a constriction, a buffer chamber filled with compressible pressure fluid, said chamber communicating with said other pressure sensitive means.
